UNITED STATES PATENT OFFICE.

ALEXANDER KNAPPENBERGER, OF SIEGFRIED, PENNSYLVANIA, ASSIGNOR TO JOHN J. KOCHER AND JOHN KNAPPENBERGER, BOTH OF NORTHAMPTON, PENNSYLVANIA.

CRUSHING-MILL.

1,003,362.

Specification of Letters Patent. Patented Sept. 12, 1911.

Application filed November 16, 1910. Serial No. 592,691.

To all whom it may concern:

Be it known that I, ALEXANDER KNAPPENBERGER, a citizen of the United States, residing at Siegfried, in the county of Northampton and State of Pennsylvania, have invented new and useful Improvements in Crushing-Mills, of which the following is a specification.

This invention relates to improvements in 10 crushing mills such as are usually employed for crushing cement, clinker and the like.

One object of the invention is the provision of a crushing mill including a rotatable platform supporting the crushing rollers and underlying a hopper and having openings through which the material to be crushed is directed by centrifugal force to fall on a platform over which the rollers pass.

20 Another object is the provision of an improved feed mechanism for transporting the material to be crushed from the platform onto the ring die.

A further object is the provision of an improved mounting and bearing for the crushing rollers.

With these and other objects in view, which will more fully hereinafter appear, the present invention consists in certain 30 novel details of construction and arrangement of parts, hereinafter fully described, illustrated in the accompanying drawings and more particularly pointed out in the appended claims; it being understood that 35 various changes in the form, proportion, size, and minor details of the device may be made, within the scope of the appended claims, without departing from the spirit or sacrificing any of the advantages of the invention.

In the accompanying drawings, forming part of the specification; Figure 1 is a vertical sectional view of the device. Fig. 2 is a sectional plan view approximately on the 45 line 2—2 of Fig. 1. Fig. 3 is a detail plan view of the bed with the rollers removed. Fig. 4 is a detail perspective of one of the rollers and its shaft. Fig. 5 is a detail perspective of one of the roller hangers showing 50 a fan blade secured thereto.

Similar numerals of reference are employed to designate corresponding parts throughout.

The bed comprises a circular platform 55 designated by the numeral 5. This member is provided adjacent to its periphery with a

plurality of spaced arcuate-shaped vertical openings 6, and depending from the lower face of the platform is a chute. The chute is made up of outer and inner sections 7 and 8, the outer section 8 being suitably secured to the lower face of the platform and at the outer sides of the openings 6, while the inner section 7 is concentric with the outer section 8 and is arranged at the inner sides of the openings 6, the crushed material passing, in a manner to be described later through the openings 6 and thence through the space between the sections 7 and 8.

Rising from the upper face of the platform 5 are concentrically disposed plates 9 and 10, the said plates 9 and 10 being arranged on the opposite sides of the openings 6, the inner of said plates being made up of a plurality of sections corresponding in length 75 to the distance between the adjacent ends of the openings 6. With this construction it will be manifest that the crushed material passing between the adjacent ends of the sections of the inner plate will fall into the 80 openings 6 and thence through the chute in the manner before described.

Inclining upwardly and inwardly from the upper face of the platform 5 are four or more uprights designated by the numeral 11. The lower ends of the uprights are bolted or otherwise secured to the bed 5 beyond the openings 6 and at their upper ends are connected by a circular head block 12. Secured to the medial portions of the 90 uprights 11 is a circular platform 13, the function of which will appear later. Connection between the platform 13 and plates 9 and 10 is established by means of concentrically disposed circular walls of wire netting designated by the numerals 14 and 15 which form the body of the crushing chamber. By reference now to the drawings it will be seen that the bed 5 is provided on its upper face with a concentrically disposed circular channel, the floor of which is inclined upwardly and outwardly as shown at 16. The outer or highest point of the floor of the channel lies adjacent to the inner sides of the openings 6. Arranged 95 within the channel is a ring die, the said ring die comprising a bearing portion 17 shaped to the configuration of the floor 16 of the channel, but somewhat greater in width than the width of said floor, so that 100 when its inner side bears on the inner side of the channel the outer side thereof will

bear on the inner concentric plate 10. The bearing portion 17 is somewhat less in thickness than the width of the inner side wall of the channel so that when the inner side of the bearing portion bears on said inner side wall a space will exist between the upper surface of the bed 5 and the upper surface of the inner side portion of the bearing plate, for a purpose to be described later.

Rising from the outer side portion of the bearing plate 16 is a vertical flange 18 having a plurality of spaced vertical recesses to align with the space between the adjacent ends of the sections of the inner plate 10. With this construction it will be manifest when the material is crushed in a manner to be presently described on the upper surface of the portion 17 of the ring die and passes through the openings in the flange portion 18 thereof it will fall into the chute in the manner before described.

The drive shaft is designated by the numeral 19 and is journaled in suitable boxings in the central portion of the head block 12 and platform 13. A pulley 20 is keyed or otherwise secured to the shaft 19 at a point below the head block 12. The lower end of the shaft 19 extends to the medial portion of the space between the platform 13 and bed 5.

Fixedly secured to the lower end portion of the shaft 19 is a collar 21 having a pair of oppositely disposed lateral sockets. What will subsequently be termed hangers are shown to include horizontal portions 22, the inner ends of which are secured in the sockets of the collar, and the outer ends of which terminate in downwardly and outwardly inclined extensions 23, the lower ends of which extend to points a trifle above the concentric plates 9 and 10, and adjacent to the inner wall 15.

The bed 5 is formed with a central opening, and surrounding this opening is a bearing block 24, the upper surface of which is beveled as shown at 25. Extending through the opening in the bed 5 is a shaft 26, the lower end portion of which extends beyond the lower face of the bed 5 and is screw-threaded to engage with a nut 27.

The upper end portion of the shaft 26 is provided with an axially threaded bore. Arranged on that portion of the shaft extending above the upper face of the bed 5 is a frusto-conical-shaped block 28 and housing the block 28 is a hollow frusto-conical-shaped boxing 29, the lower end portion of which is provided with an inturned flange 30, to bear on the beveled surface 25 of the bearing block 24. The upper end portion of the boxing 29 is provided with a top plate 31, having a central opening to receive the upper end portion of the shaft 26. Screwed into the threaded bore of the

shaft 26 is the shank 32 of a bolt, the head 33 of said bolt bearing on the top plate 31 and co-operating with the upper end of the block 28 to hold the top plate 31 against vertical movement, the bolt, however, not preventing rotation of the boxing 29. The boxing 29 is provided with a pair of diametrically opposite openings which receive the inner ends of shafts 34 and 35, the outer ends of said shafts being journaled in the lower end portions 23 of the hangers. Owing to the relative lengths of the boxing 29 and portions 23 of the hangers the shafts 34 and 35 will incline upwardly from the boxing 29. The shafts 34 and 35 are formed with crushing rollers or wheels 36 and 37, the width of the tread surface of these rollers being somewhat less in width than that of the portion 17 of the ring die, the said rollers being so positioned that their outer sides will bear on the flange 18 of the ring die, while the space will exist between the inner side of said rollers and the adjacent side of the channel of the bed 5 as clearly shown in Fig. 1. In order that a maximum amount of the outer side of the rollers 36 and 37 will bear on the inner surface of the flange 18 of the ring die, the outer surfaces of said rollers are curved to correspond to the curvature of the said flange 18 so also are the tread surfaces of the rollers shaped to correspond to the curvature and inclination of the portion 17 of the ring die.

Surrounding the lower end portion of the shaft 19 and supported from the horizontal portion 22 of the hanger is a circular table 38, the said table being provided adjacent to its periphery with diametrically disposed vertical openings 39 and 40. Extending downwardly and outwardly from the openings 39 and 40 are spouts 42 and 43, the axial portions of said spouts lying in an inclined plane with the middle of the bearing portion 17 of the ring die, the said spouts being so positioned that the material passing therethrough will be discharged immediately in front of the rollers 36 and 37 when the latter are rotating in the direction of the arrows shown in Fig. 1. The table 38 is peripherally provided with a vertical wall 44 extending upwardly to the middle portion of the space between the platform 13 and the table.

The platform 13 is provided with oppositely disposed openings 45 and 46 located to one side of the center of said platform. Inclining downwardly and inwardly from the lower ends of said openings are tubes 47 and 48, the lower end portions of which extend over the upper side of the wall 44 of the table so that the material passing therethrough will fall onto the table 38. Inclining upwardly and inwardly from the upper sides of the openings 45 and 46 are tubes 49 and 50, the upper or inner ends of which

lead into the lower end of a hopper 51. With this construction it will be manifest when the material to be crushed is inserted into the hopper 51 it will pass through the 5 tubes 49 and 50, thence through the openings 45 and 46 into the tubes 47 and 48 and onto the table 38. When the latter is rotated by means of the shaft 19 the material on the table 38 is thrown outwardly by centrifugal. 10 force and passed through the openings 39 and 40 and into the spouts 42 and 43 through which it will fall onto the bearing portion 17 of the ring die to be crushed by the rollers 36 and 37 as the latter rotate.

15 It is manifest that a portion of the material to be crushed will fall onto the platform 5 and into the space between the channel and bearing block 24. In order that this material may be conveyed to the bearing 20 plate the shafts 34 and 35 are provided between the inner sides of the rollers and their inner ends with spiral conveyers 53 and 54. These conveyers are fixedly secured to the shafts in any preferred manner, and it will 25 be manifest as the shafts rotate that the material falling on the bed 5 will, by the action of the conveyers be moved outwardly and onto the bearing portion 17 of the ring die, the said material first falling into the space 30 between the side wall of the channel and inner sides of the rollers from whence it will be forced by new material being added into a position to be operated upon by the rollers 36 and 37.

35 It will be manifest that during the operation of crushing more or less dust will rise as the material falls on the ring die or onto the platform 5. In order that this dust may be agitated and finally forced through the 40 inner wall of screen wire fan blades 56 and 57 are provided. These members are preferably formed of single pieces of sheet metal right triangular in contour and are secured in inverted position to the outer 45 sides of the portions 23 of the hangers, the said blades being suitably shaped to direct the dust through the inner wall 15 from whence it will pass either from the outer wall or downwardly into the space between 50 said walls and finally into the chute.

From the foregoing, it is evident that I have provided a device which is comparatively simple in structure and inexpensive to manufacture, embodying few parts and 55 these so arranged that the danger of derangement will be reduced to a minimum.

I claim:—

1. In a crushing mill, a bed plate provided with a plurality of spaced vertical 60 openings, a chute depending from the lower ends of said openings, a circular plate positioned on the upper side of the bed plate and at the outer sides of said openings, and

a second circular plate formed of a plurality of sections positioned between the adjacent 65 ends of said openings and at the inner sides thereof, a ring die positioned on the upper face of said bed plate and having a vertical portion provided with openings alining with the spaces between the adjacent ends of the 70 sections of said inner wall, rollers positioned to operate on said bed plate, and means for rotating said rollers.

2. In a crushing mill, a bed plate, a ring die positioned on the upper face of said bed 75 plate, a rotatable boxing positioned centrally of said bed plate, a drive shaft, a hanger secured to said drive shaft, a roller positioned to bear on said ring die, a shaft 80 for said roller having its opposite ends journaled in said boxing and hanger, and a conveyer secured to said shaft, for the purpose described.

3. In a crushing mill, a bed plate provided with a circular channel having an inclined floor, and further provided with an outlet opening located on the said channel, a ring die having an inclined portion bearing on the inclined floor of the channel, and a vertical portion provided with an outlet 90 opening communicating with the outlet opening of the bed plate, a rotatable bearing member positioned centrally of the bed plate, a drive shaft, a hanger connected with the drive shaft, and a roller positioned to 95 bear on the ring die and having a shaft with its opposite ends journaled in said hanger and bearing member.

4. In a crushing mill, a bed plate, a die positioned on said bed plate, a crushing 100 roller adapted to operate over said die, and a conveyer carried by the crushing roll and adapted to force the material on the bed plate on to the die.

5. In a crushing mill, a bed plate, a ring 105 die positioned on the upper face of said bed plate, a crushing roll adapted to travel around over the ring die, a bearing shaft for said roller, and a conveyer carried by the bearing shaft and adapted to travel over the 110 bed plate.

6. In a crushing mill, a bed plate, a die positioned upon the bed plate, shaft bearings, a shaft journaled therein, a crushing member carried by the shaft and adapted to 115 operate over the die, a conveyer carried by the shaft and adapted to force material on the bed plate toward the die, and means to positively rotate one of said bearings.

In testimony whereof I affix my signature 120 in presence of two witnesses.

ALEXANDER KNAPPENBERGER.
